DESIGN FOR A COMBINED DENTAL LABORATORY BENCH AND CABINET

Edwin D. Beebe, Rochester, N. Y., assignor to
Ritter Company, Inc., Rochester, N. Y., a corporation of Delaware

Application May 5, 1945, Serial No. 119,409

Term of patent 14 years

(Cl. D16—2)

To all whom it may concern:

Be it known that I, Edwin D. Beebe, a citizen of the United States, residing at Rochester, in the county of Monroe and State of New York, have invented a new, original, and ornamental Design for a Combined Dental Laboratory Bench and Cabinet, of which the following is a specification, reference being had to the accompanying drawing, forming part thereof.

The figure is a perspective view of a combined dental laboratory bench and cabinet showing my new design. The side at the left, not shown, is substantially plain.

I claim:

The ornamental design for a combined dental laboratory bench and cabinet, substantially as shown and described.

EDWIN D. BEEBE.
